UNITED STATES PATENT OFFICE.

THOMAS BENN ELLWOOD, SR., OF MARSHALL, TEXAS, ASSIGNOR OF SIXTY ONE-HUNDREDTHS TO ALOIS P. PRENDERGAST, OF DALLAS, TEXAS.

UNIVERSAL COMBINATION INTERLOCKING AND CLAMPING DEVICE.

Application filed June 25, 1925. Serial No. 39,572.

This invention relates to means for mounting and firmly holding in position objects of irregular shapes and dimensions while being operated upon by a workman, and at the same time enabling the object to be quickly adjusted into any position and firmly held in said adjusted position.

Many objects of very considerable weight and of irregular shape are nevertheless so constructed that they cannot be gripped or clamped in a vise without great liability of injuring the same. Moreover, many objects such as lubricators for locomotives, injectors for locomotive boilers, air motors, air-brake distributing valves; typewriters, etc., are of such an irregular shape and, in making repairs, access has to be had to the same from so many different sides and angles that it is essential that they be turned or shifted to enable the workman to get at the particular part needing repair or treatment. In structures heretofore used to support such objects, much time and labor have been consumed in dismounting the same and remounting them in adjusted position.

The object of the present invention is to provide a mounting for such structures which shall hold the structure firmly in any given position and which, without dismounting it from the support, can be quickly and readily adjusted into any desired position, inclined, upside down, reversed, or otherwise, and firmly held in such adjusted position.

A further object is to provide means for safely and firmly holding the object without injury to the object or any of its parts. Where objects such, for example, as injectors for locomotive boilers, while of great weight, are of irregular shape and with very light walls, difficulty has been experienced in mounting the same with sufficient rigidity or firmness without at the same time crushing or partially crushing some of the parts of the object and thereby destroying it for the purposes for which it is made. The mounting of such devices requires great care and the consumption of much time by the workman, and when the device has to be turned over or turned around or inclined at an angle for the operations to be performed thereon, this involves much additional time on the part of the workman in dismounting the object and remounting it into the desired position.

A further object of the present invention, therefore, is to provide a mounting for such structures on which the structure or object may be once firmly secured and thereafter readily and quickly adjusted into any desired position and firmly held therein without the necessity of dismounting and remounting the same.

Further objects will appear in connection with the description of the invention which follows. The inventive idea is capable of receiving a variety of mechanical expressions, some of which for the purpose of illustrating the invention are shown in the accompanying drawings, but it is to be expressly understood that such drawings are for the purposes of illustration and are not designed to define the limits of the invention, reference being had to the appended claims for this purpose.

In said drawings—

Fig. 1 is a side elevation of one form which the invention may assume;

Fig. 2 is a top plan view of Fig. 1, with the parts shown in adjusted position in dotted lines;

Fig. 3 is a section on the line 3—3 of Fig. 1;

Fig. 4 is a section on line 4—4 of Fig. 1, with the operating handle shown in unlocked position;

Fig. 5 is a side elevation of Fig. 1, looking from the right;

Fig. 6 is a vertical section on the line 6—6 of Fig. 5;

Fig. 7 is a side elevation of a modified form of the mounting;

Fig. 8 is a plan view of Fig. 7;

Fig. 9 is a vertical section on the line 9—9 of Fig. 7; and

Fig. 10 is a side elevation, partly in section, showing a form of the invention in which a tool maker's vise constitutes a part of the work-attaching element.

In said drawings, in which like reference numerals refer to like parts throughout the several views, 1 is a metal socket-piece having a flange 2 through which extend bolts 3 by means of which it is secured to any suitable support, as a work-bench. This socket-piece has a tapering opening 4 formed therethrough to receive the lower tapered end 5 of vertical stem or column 6 with a snug fit. A collar 7 is mounted to closely fit the stem so as to be free to slide vertically

thereon, and a pin 8 is passed through the collar and through a slot 9 in the stem, said pin serving to prevent the collar 7 from turning on the stem, to limit the vertical movement of the collar on the stem, and by reason of the close fit of the pin 8 preventing play between the collar and stem. A screw 10 (Fig. 6) accessible through an opening 11 in the collar is employed to take up any wear on the part of the pin 8.

Referring to Figs. 1 and 5, 12 indicates a series of vertical teeth on the upwardly extending flange portion of the socket-piece 1, which teeth are engaged by corresponding interlocking teeth 13 on the collar 7. By this construction, the column 6 may be freed from the socket-piece 1 by simply raising the collar 7 when the column is free to be turned on its vertical axis through any desired angle. The collar may then be again lowered until the teeth on the collar engage those on the socket-piece and the column is again firmly held in its adjusted position. This adjustment takes but an instant and can be easily effected even with a heavy weight mounted upon the structure.

The upper end of the column 6 has a horizontal bore or opening formed therein and above this bore or opening the column is split so as to provide two ears 14, 15 (Figs. 4 and 5). The ear 14 is screw-threaded and the pin 16 passes freely through an opening in the ear 15 and is screw-threaded into the ear 14 as will be readily understood by an inspection of Fig. 4. The pin 16 extends some distance outside of ear 15 and has a handle 17 secured to its outer end by a pin 18. The end of the handle, where it is secured to the pin 16 is forked so as to embrace the end of the pin, and the ends of these forks are eccentrically formed so as to provide on either side cams 19. By means of the handle the pin 16 may be turned so as to draw the two split ears 14 and 15 close together or permit them to slightly separate by their natural elasticity into the position shown in Fig. 4. This turning action of the screw 16 can be accomplished by turning the handle and when the screw has been operated to bring the split ears 14 and 15 close together, the handle being extended horizontally as shown in Fig. 4, the same may then be turned in either direction, upward or downward as shown in Fig. 1, when the cam 19, acting against a washer 20 surrounding the pin 16 between the cam end of the handle 17 and the ear 15, acts to quickly and firmly force the ears tightly together.

Passing through the opening in the upper end of the column 6 is a laterally extending work-supporting member, preferably in the form of a rod or tube 21, the outer diameter of said tube being preferably such as to permit it to slide freely in the opening in the

top of said column 6, when the parts are in the position shown in Fig. 4, that is, in unclamped position. Said tube 21 has removably secured thereon a flanged collar 22 preferably through the medium of a taper pin 23 passing through the collar and the tube 21. For the purpose of adjusting this collar to any desired position on the tube 21, a series of holes or openings 24 may be provided in the tube, as clearly shown in Fig. 1. The flanged edge of the collar 22 adjacent to the column 6 is provided with teeth 22' engaging corresponding teeth 25 on the stem 6. By loosening the clamping ears 14 and 15, the tube 21, and with it the collar 22, may be removed to the left (Fig. 1) so as to disengage the teeth 22' from the teeth 25, when the tube 21 may be turned around its axis through any desired angle and the tube then moved to the right (Fig. 1) until the teeth 22' again engage the teeth 25 and said tube then clamped in position by turning the clamping screw 16 until the parts are fairly well closed, when the final tightening action may be quickly secured by throwing down the handle 17 to the position shown in Fig. 1, whereby the cams 19 will act on the washer 20 and cause the tube 21 to be tightly gripped.

On the end opposite the collar 22, the tube 21 is provided with an opening beyond which extend ears 26, 27. One side of this opening, and as shown in Fig. 1 the underside, is provided with a toothed flange 28. Extending through the opening in the work-supporting member, 21, is a bar or tube 29 which has a toothed sleeve 30 secured thereon by a taper pin 31. An anvil or other work attaching device 32 is secured on the bar or tube 29, which latter is clamped in position on the tube or bar 21 precisely as said bar 21 is clamped in position on the column 6, the clamping being effected through the operation of the screw and cam handle as will be readily understood from an inspection of Fig. 3.

The object to be mounted may be firmly secured through the medium of bolts or otherwise to the anvil 32 mounted on the upper end of the member 29.

Let it be assumed that, when the object is mounted upon the anvil 32, it is desired to perform some operation on the back of the object from the position that it would occupy in Fig. 1. The operator raises the sleeve 7 and turns the column around its vertical axis, say until the parts assume the position shown in dotted lines in Fig. 2. During this operation the anvil-supporting member 29 remains firmly clamped and locked to the laterally extending work-supporting member 21, which member in turn is firmly held in the upright column 6. When the parts have reached the adjusted position desired, the sleeve 7 is lowered un-

til the teeth thereon engage the teeth on the socket-piece 1, when the whole will be firmly and irremovably fixed. Now, let it be assumed that it is desired to turn the object 5 down so that the workman may get at the bottom part thereof. By properly operating the handle 17 he may loosen the ears 14 and 15 so as to permit the work-supporting member 21 to be moved far enough to the 10 left to disengage the teeth 22' and 25, when the member 21 may be turned on its axis through any desired angle and then moved back to the right until the teeth 22' and 25 are in engagement when the part 21 may be 15 clamped in position by operating the handle 17, a preliminary clamping action being secured by means of the screw 16 and the final clamping action being secured through the cams on the handle portion 17. The 20 anvil 32 and the supported object 33 will then be in the position shown in dotted lines in Fig. 1.

By an inspection of Fig. 5, it will be 25 readily perceived that the anvil 32 may be readily inclined at any angle and secured in such inclined position by operating the clamping handle and screw for opening and closing the clamping ears 14 and 15, and that while in such inclined position it may 30 be turned through any desired angle around the axis of the anvil stem 29 by opening and closing the clamping ears 26, 27.

Referring now to Figs. 7, 8 and 9, there 35 is therein shown a form of work support differing from that of the anvil shown in Fig. 1. Some objects upon which work is to be performed have a projecting part in the form of a rod or strong tubular portion which may be clamped without injury there- 40 to, and the construction shown in Figs. 7, 8 and 9 provides a work support for objects of this character.

Located in the opening formed in the arm or member 21 is a ring split into two parts 45 35, 35' and provided with an outwardly extending horizontal flange 36 through which extends a pin 37 entering a socket or depression 38 formed in the member 21. Preferably, the opening through the arm 50 21 in which the split ring is located is tapered inward from top to bottom as will be readily understood from an inspection of Fig. 9. The pins 38 serve to hold the two members 35, 35' of the split ring in such 55 a position that their line of cleavage or separation is exactly along the line between the two ears 26, 27 of the arm or member 21. When any object, as the tubular member 39, is to be mounted, the two members 35, 35', 60 of the split ring are placed around it and the split ring then dropped into the opening in the arm 21 with the pins 37 entering pin holes or sockets 38, and when the ears 26, 27 are forced together into the clamping 65 position by means of the screw and the cam

handle, as heretofore described, the members 35, 35' of the split ring are forced into close clamping action upon the tubular member 39. It will be readily understood that split rings having varying internal 70 diameters may be employed and that thereby the device may be adjusted so as to suitably clamp tubular members of varying diameters.

Referring now to Fig. 10, there is therein 75 shown a tool-maker's vise carried by the work-supporting member 21. Extending through the opening in said work-supporting member is a bar or tube 29' which has thereon a toothed collar 30' secured thereto preferably by a taper pin 31', which pin plays in a vertical slot 40. On the lower end of the tube or stem 29' is a collar 41 secured preferably by a taper pin 42, and a spring 43 reacts between the collar 41 and the toothed collar 30' so as to normally hold the teeth thereon in engagement with the teeth 28 surrounding the opening in the work-supporting member 21. The collar 30', however, may be readily depressed 80 against the tension of spring 43 by downward pressure on the pin 31' so as to disengage the teeth thereon from the teeth 28 on the work-supporting member, when the bar or tube 29' may be turned on its axis 85 to any desired angle. The clamping ears 26, 27 have, of course, been loosened and, upon releasing the pressure from the pin 31, the spring 43 will again force the toothed collar 30' upward so that the teeth thereon 90 will engage the teeth 28 on the work-supporting member 21, after which the clamping ears 26, 27 are tightened as before described.

Carried on the top of the column 29' is 95 a suitable anvil 32' to which the vise 44 is firmly bolted. The jaws of the vise are opened and closed through the action of the vise screw 45 passing through the nut 46 secured to one of the jaws. The rod upon which the screw 45 is formed is extended outward to the right as shown in Fig. 10 and a spring 47 surrounds the same and reacts between the nut 46 on the inner jaw 48 of the vise and a downwardly depending lug 49 on the outer jaw 50, a washer 51 being 100 preferably interposed between said lug and spring. The outer end of the rod has a handle 52 attached thereto, the construction and connection of the parts being precisely similar to that shown in Fig. 4, the handle 52 having cams similar to those 19 shown in Fig. 4 and reacting against a washer 53 just as the cams 19 react against the washer 20 in Fig. 4. By this construction the vise 105 holding the tool to be operated upon may be opened and closed through the medium of the handle 52; the vise may be turned through any desired angle around the column 6, the work-supporting member 21 may 110 115 120 125 130

be turned through any desired angle around its axis and the vise itself may be readily adjusted around the axis of the tube or bar 29', thus rendering possible the adjustment 5 into any position that may be desired by the tool maker and with the minimum expenditure of time and effort.

From the foregoing it will be seen that the invention involves a structure wherein 10 objects, even though of very material weight, may, when once mounted, be readily and quickly shifted into a great variety of positions, and when so shifted can be firmly held in the shifted or adjusted position, and that 15 by the use of the invention great saving in time can be accomplished and without danger of injury to the object mounted thereon.

It will be understood that the invention is capable of being embodied in a variety of 20 mechanical structures without departing from the spirit of the invention. Such variations and modifications as fall within the spirit of the invention are intended to be included in the terms of the accompanying 25 claims.

What is claimed is:—

1. The combination of a socketed base piece, a column mounted in said base, and a work-supporting member slidably mounted 30 transversely to said column, an annular series of slidable interlocking shoulders on said column engaging corresponding shoulders on said base, and slidable interlocking shoulders on said work-supporting member 35 engaging complementary shoulders on the column.

2. The combination of a column having a series of teeth around its lower portion and a series of teeth around a split opening in 40 its upper portion, with a socketed base having a series of teeth engaged by the teeth on the lower portion of the column, a transverse work-supporting member passing through said split opening and having a 45 series of teeth engaging those around said opening, and means closing said split opening into clamping engagement with said member.

3. The combination of an upright column 50 having a tapered lower end and a transverse opening surmounted by split ears in its upper portion, with a base having a tapered socket and a toothed flange surrounding the upper end of said socket, a collar slidably 55 mounted on said column and having a toothed edge engaging the toothed flange of the socket, a work-supporting member extending through said transverse opening in the column, a series of teeth surrounding 60 said transverse opening and engaged by a complementary series of teeth on said work-supporting member, and means clamping said member in said transverse opening.

4. The combination of a socketed base, a 65 column and a work-supporting member, in-

terlocking shoulders on said base and column, an annular series of shoulders on said column, a longitudinally adjustable collar on said work-supporting member, said collar having shoulders in interlocking engagement with said series of shoulders on the column, and means restraining said collar from rotation relative to said work-supporting member. 70

5. The combination of an upright column, a transverse work-supporting member and a work-attaching device extending transverse to said member, an annular series of interlocking shoulders on said column and member, an annular series of interlocking shoulders on said device and member, and means holding said two sets of shoulders in interlocking engagement. 75

6. The combination of an upright column having a split opening in its upper portion, means mounting said column to turn on a vertical axis, interlocking shoulders on said column and mounting to hold the column in adjusted position, a work-supporting member extending slidably through said transverse opening, and a combined screw and cam clamping device securing said member in said opening. 80

7. The combination of an upright column adjustable around its vertical axis and having a transverse opening surmounted by split ears in its upper portion, with a work-supporting member extending slidably through said opening, and a screw-threaded rod passing freely through one of said ears and engaging the screw-threads of the other ear, and a handle pivoted to said rod and having a cam formed on its end portion adjacent the non-screw threaded ear, whereby the said work-supporting member may be 100 clamped in said transverse opening through the combined action of said screw and cam. 95

8. The combination of a vertical column, a laterally extending work-supporting member carried by said column, said work-supporting member being provided with a transverse opening having split ears extending therefrom, a work-attaching device extending slidably through said opening, said member and device having complementary interlocking shoulders held in yielding engagement one with the other, a screw-threaded rod extending freely through one of said ears and screw-threaded into the other ear, a handle pivoted to the end of said screw-threaded rod, and a cam on the end of the handle adjacent the non-screw threaded ear, whereby said work-attaching device may be clamped in said member by a combined screw and cam action. 110 120

9. The combination of a vertical column having a transverse work-supporting member secured in its upper end portion, a toothed collar surrounding the lower portion of said column, a pin extending through 125 130

said collar and through a longitudinal slot in said column, whereby said collar has a limited sliding motion upon the column, a socketed base piece receiving the lower end 5 of said column, a toothed flange on said base piece, and a toothed flange on the lower end of said collar engaging the teeth on the base piece, whereby said column may be adjusted to any desired angle and locked in such ad-
10 justed position.

10. The combination of an upright column adjustable around its longitudinal axis, a

transverse work-supporting member slidably carried thereby and adjustable around its longitudinal axis, a work-attaching device 15 including a vise adjustable around an axis transverse to the work-supporting member, means locking said elements in their ad-justed positions, and combined screw and cam mechanism actuating the jaws of said 20 vise.

In testimony whereof I have signed this specification.

THOMAS BENN ELLWOOD, SR.
